(57) CLAIM

The ornamental design for a cosmetic applicator, as shown and described.

DESCRIPTION

FIG. 1 is a front view of a cosmetic applicator of the present invention.

FIG. 2 is a rear view thereof.

FIG. 3 is a top plan view thereof.

FIG. 4 is a bottom view thereof.

FIG. 5 is a right side view thereof.

FIG. 6 is a left side view thereof.

FIG. 7 is a perspective view thereof.

FIG. 8 is an enlarged front view thereof, taken along the line 8-8 of FIG. 1.

FIG. 9 is an enlarged left side view thereof; and,

FIG. 10 is an enlarged perspective view thereof, taken along the line 10-10 of FIG. 7.

The broken lines showing portions of the cosmetic applicator form no part of the claimed design.
